UNITED STATES PATENT OFFICE

JOHN M. SHERWIG, OF SHARON, PENNSYLVANIA

DIRIGIBLE HEADLIGHT

Application filed October 11, 1929. Serial No. 398,916.

The present invention relates to a dirigible headlight for automobiles and has for its prime object to provide a headlight which is turnable to cast its light in the direction in which the automobile is moving at all times so as to provide proper illumination when rounding curves and the like.

Another important object of the invention resides in the provision of a mechanism of this nature which is comparatively simple in its construction, easy to install, compact and convenient in its arrangement of parts and thoroughly efficient and reliable in use and operation.

With the above and numerous other objects in view as will appear as the description proceeds, the invention resides in certain novel features of construction, and in the combination and arrangement of parts as will be hereinafter more fully described and claimed.

In the drawing:

Figure 1 is a side elevation of the apparatus embodying the features of my invention showing the same installed,

Figure 2 is a partial sectional view of the headlight structure taken substantially on a transverse vertical plane, Figure 1,

Figure 3 is a sectional view taken substantially on the line 3—3 of Figure 1,

Figure 4 is a plan view of the keeper plate,

Figure 5 is a sectional view taken substantially on line 5—5 of Figure 1,

Figure 6 is a sectional view through the hollow connecting rod, and

Figure 7 is a sectional view through the socket structure of the headlights.

Referring to the drawing in detail it will be seen that the numeral 5 denotes a horizontal cross bracket plate bolted as at 6 to the side frame member 7. This bracket plate 5 is formed at its ends with upstanding ears 8 and 9.

A bushing 10 is mounted in an opening in the ear 9. A shaft 11 is journaled in the bushing 10 and through the ear 8. A vertical bracket plate 12 has laterally extending terminal ears 14 and 15. The bushing 10 extends through an opening in the bracket plate 12. A beveled gear 16 is fixed to one end of the shaft 11 and a nut 17 is threaded

on the shaft 11 so as to hold the bushing 10 in place between the beveled gear and said nut.

A tubular casing 20 extends between the ears 14 and 15 and in its ends has a pair of heads 21 and 22. The numeral 23 denotes a headlight with a shank 24 extending rearwardly therefrom and having a rounded terminal seated in a socket 25 and adjustably held therein by means of an adjusting stem 26 and nut 27.

This socket 25 is formed on the upper end of a shank 28 journaled through the ear 15 and the head 21 and extending downwardly in the casing and being hollow to receive the upper end of a shaft 29 journaled through the head 22 and the ear 14. A beveled gear 30 is mounted on this shaft 29 meshing with the beveled gear 22. A crank 31 is anchored on the other end of the shaft 11 and its extremity is pivotally engaged in a fork 32, the stem of which extends into and is fixed in a hollow connecting rod 33.

A rod 34 extends into the other end of the connecting rod 33 and is clamped there in by means of a nut 35 threaded on said other end which is split. The numeral 36 denotes a steering arm on which is engaged the clamp C which comprises a pair of L-shaped members 37 and 38 the shorter legs 80 of which are disposed in abutment with the longer legs in substantial spaced parallelism and drawn tightly together about the arm 36 by means of a bolt 39.

An L-shaped bracket 40 is bolted as at 41 to the shorter legs of the clamp members and the curved extremity 42 of rod 34 is engaged therein. A keeper plate 44 is bent at right angles as is clearly indicated in Figure 4 and has an opening 45 to receive the bolt 39 so that a portion extends along the inner side of the member 38, the other portion extends down alongside the arm 36 and is notched as at 46 in its end to fit about bolt 49 which has a head 50 receivable in socket 51 of the steering rod.

From the above detailed description it will be seen that as the steering arm 36 is rocked the rod 34 and the rod 33 will be reciprocated to rock the crank 31 thereby rock-

ing the shaft 11. The rocking of the shaft 11 through the gearing 16 and 30 will rock the shaft 27, and standard 28 thereby swinging the headlight 23 so as to direct its light in the proper direction in which the vehicle 5 may be steered.

It is thought that the construction, operation, utility and advantages of this invention 10 will now be quite apparent to those skilled in this art without a more detailed description thereof.

The present embodiment of the invention has been disclosed in considerable detail 15 merely for the purposes of exemplification since in actual practice it attains the features of advantage enumerated as desirable in the statement of the invention and the above description.

It will be apparent that changes in the 20 details of construction, and in the combination and arrangement of parts may be resorted to without departing from the spirit or scope of the invention as hereinafter claimed or sacrificing any of its advantages.

Having thus described my invention, what 25 I claim as new is:

1. A dirigible headlight apparatus of the 30 class described comprising a bracket structure, a vertical shaft in the bracket structure, a horizontal shaft in the bracket structure, gearing operatively connecting the shafts, a headlight, means engaging the headlight with the vertical shaft to swing upon the rotation thereof, a crank on said 35 horizontal shaft, a link structure connected with said crank, a clamp for connecting the link structure with the steering arm of an automobile, said clamp comprising a pair of L-shaped members having their shorter legs overlapping an L-shaped bracket mounted on the overlapped legs and a bolt 40 through the said legs and the bracket for securing the same together, and adapted to have their longer legs straddling the arm, 45 and a bolt extending through the longer legs to draw them tightly about said arm, said link structure adapted to be attached to said L-shaped bracket.

2. A dirigible headlight apparatus of the 50 class described comprising a bracket structure, a vertical shaft in the bracket structure, a horizontal shaft in the bracket structure, gearing operatively connecting the shafts, a headlight, means engaging the headlight with the vertical shaft to swing upon the turning thereof, a crank on said horizontal shaft, a 55 link structure connected with said crank, a clamp for connecting the link structure with the steering arm of an automobile, said clamp comprising a pair of L-shaped members having their shorter legs bolted together and to the link structure and their longer legs straddling the arm, and a bolt extending 60 through the longer legs to draw them tightly 65 about said arm, a keeper plate bent over upon

itself intermediate its ends and having an opening to receive the bolt so that a portion 70 may be disposed along the inner side of one clamp member while the remaining portion extends down alongside of the arm to engage against the ball thereof, for preventing the clamp from accidental downward displacement from position on the arm.

3. A dirigible headlight apparatus of the 75 class described comprising a bracket structure, a vertical shaft in the bracket structure, a horizontal shaft in the bracket structure, gearing operatively connecting the shafts, a headlight, means engaging the headlight with the vertical shaft to swing upon the turning 80 thereof, a crank on said horizontal shaft, a link structure connected with said crank, a clamp for connecting the link structure with the steering arm of an automobile, said clamp comprising a pair of L-shaped members having their shorter legs in overlapping relation 85 and their longer legs straddling the arm, an angle bracket secured to said overlapping legs, a bolt through the bracket and the overlapped legs, means on the angle bracket for attaching the link structure and a bolt extending through the longer legs to draw them tightly about said arm, a keeper plate bent over upon itself intermediate its ends and having an opening to receive the bolt through 90 the longer legs so that a portion may be disposed along the inner side of one clamp member while the remaining portion extends down alongside of the arm for engaging the ball projection for limiting the accidental 95 downward displacement of the clamp, a horizontal transverse bracket means and means for attaching the bracket plate to a chassis channel bar, said bracket plate having upstanding ears in which the horizontal shaft is 100 journaled.

4. A dirigible headlight structure for a 105 motor vehicle comprising a side frame member of a motor vehicle chassis, a horizontal bracket plate having upturned ears on each 110 end and attached at a point near one end upon said member, and a bolt through said plate and said member, and a vertical bracket plate having laterally directed ears on its ends and secured at its lower end to one of said 115 upturned ears; and a horizontal shaft journaled through the upturned ears and the vertical bracket plate, and a bushing on the end of the shaft entering the upturned ear and the vertical bracket plate, and a screw threaded portion on the same end of the shaft carrying a nut for clamping against the bushing; and a tubular casing vertically mounted within and between the laterally directed ears of 120 the vertical bracket plate, heads in the ends of the casing, and a hollow spindle depending into said casing, through the upper laterally directed ear and the upper head of the casing and provided with an integral flange for resting 125 on the upper face of the upper laterally 130

directed ear, and a headlamp adjusting socket on the upper end of the hollow spindle, a head lamp having a rearward projection for engagement on said socket and adjustable clamping means associated with said socket; 5 and a vertical shaft within the casing having its upper end within the said hollow spindle and its lower end journaled through the lower head of the casing and the lower ear, and an adjustable collar clamped on the lower end 10 of the vertical shaft and against the lower face of the lower ear for retaining the shaft against upward displacement, and a pinion positioned within the tubular casing and secured on the end of the horizontal shaft and 15 another pinion meshed with pinion and secured on the vertical shaft for rotating the headlamp upon rotation of the horizontal shaft, and means connecting the steering arm of the motor vehicle with the said horizontal shaft for rotating the same as the vehicle is 20 turned.

In testimony whereof I affix my signature.
JOHN M. SHERWIG.
